The ornamental design for an isokinetic oscillating exerciser, as shown and described.

DESCRIPTION

FIG. 1 is a top left side oblique view of an isokinetic oscillating exerciser showing my new design;

FIG. 2 is a front elevation view thereof;

FIG. 3 is rear elevation view thereof;

FIG. 4 is a right-side elevation view thereof;

FIG. 5 is left-side elevation view thereof;

FIG. 6 is a top plan view thereof; and,

FIG. 7 is a bottom plan view thereof.

The grip shown in broken lines forms no part of the claimed design.

Shading lines are to show contours rather than surface ornamentation.
